UNITED STATES PATENT OFFICE.

CHARLES H. SCAMMELL, OF NEW YORK, N. Y., ASSIGNOR TO THE ROEBLING CONSTRUCTION COMPANY, OF NEW YORK, N. Y., A CORPORATION OF NEW JERSEY.

EXPANDED METAL LATH.

1,087,511.

Specification of Letters Patent. Patented Feb. 17, 1914.

Application filed May 7, 1910. Serial No. 559,939.

To all whom it may concern:

Be it known that I, CHARLES H. SCAMMELL, a citizen of the United States, residing at New York, county of New York, and State 5 of New York, have invented certain new and useful Improvements in Expanded Metal Lath, fully described and represented in the following specification and the accompanying drawings, forming a part of the 10 same.

This invention relates to expanded metal lath of that class formed by slitting the metal and drawing out the strands to open the slits and turn the strands at an angle 15 to the plane of the metal and which is used generally as lathing to hold plaster in building construction, although applicable also to other uses.

Such metal lath has heretofore been made 20 and handled in large sheets, involving large expense in handling and shipment and great inconvenience and waste of material in use.

The present invention provides a new article of manufacture consisting of a roll of 25 expanded lath, by which the above objections are entirely avoided, and other important advantages secured in the manufacture, handling and use of expanded metal lath.

30 In the accompanying drawings forming a part of this specification, a roll of expanded metal lath embodying the invention is illustrated, in which--

Figure 1 is a perspective view of the roll. 35 Fig. 2 is a plan view on a larger scale of a sheet piece of the sheet forming the roll, with the central portion broken away. Fig. 3 is a detail section of the metal.

In the drawings, the roll A is formed of 40 the expanded metal lath a, the size of the roll depending upon the quantity of metal lath desired, and the roll being shown as held in form by wire ties 1, which holding means may, of course, be varied. The lath 45 has its strands 2 forming the mesh turned at an angle to the plane of the metal, as shown in Fig. 3, and the edges of a continuous sheet forming the roll are trimmed evenly in the process of manufacture, as 50 shown at 3 in Fig. 2, so as to make the sheet and roll of uniform width, and avoid the irregular and bent edges which are produced in manufacturing such lath. This roll of expanded metal lath is much cheaper and

more convenient in packing, handling, shipment and use than the large sheets heretofore used, the large economy in space and convenience in handling being apparent. In use, the roll may readily be put into and held in position and the quantity required unrolled in place and cut off, so that the inconvenient lifting and holding in place of large sheets is avoided, and material is saved as only just the quantity to be used is cut off and the lapping frequent with the old sheets avoided. The trimming of the sheet at opposite sides of the roll produces even edges, avoiding the tearing of the hands liable to occur in handling the torn and bent strands of untrimmed sheets, and the lath 70 packs more closely in the roll as there are no bent ends to separate the layers, and this trimming also secures even ends so that the edges of the sheet will not bend when the roll strikes on its end. 75

What I claim is:—

1. A new article of manufacture consisting of a package roll of expanded metal lath formed by rolling up a sheet of lath having the strands turned at an angle to the plane 80 of the metal.

2. A new article of manufacture consisting of a package roll of expanded metal lath formed by rolling up a sheet of lath having the strands turned at an angle to 85 the plane of the metal, and having the opposite edges of the lath trimmed to form a sheet of uniform width and even ends of the roll.

3. A new article of manufacture consisting of a package roll of expanded metal lath formed by rolling up a sheet of lath stretched longitudinally of the sheet and transversely to the slits, and having the strands turned at an angle to the plane of 95 the metal, said metal being rolled up in the direction in which it is stretched, and having the opposite edges of the lath trimmed to form a sheet of uniform width and even ends of the roll. 100

In testimony whereof, I have hereunto set my hand, in the presence of two subscribing witnesses.

CHARLES H. SCAMMELL.
